(57) **CLAIM**

The ornamental design for camera support having kinematically reconfigurable legs, as shown and described.

DESCRIPTION

FIG. 1 is a perspective view of a camera support having kinematically reconfigurable legs showing our new design, the portions of the camera in broken lines are shown for illustrative purposes only and form no part of the claimed design.

FIG. 2 is a right elevational view thereof;

FIG. 3 is a top plan view thereof;

FIG. 4 is a front elevational view thereof;

FIG. 5 is a bottom plan view thereof;

FIG. 6 is a rear elevational view thereof; and,

FIG. 7 is a left elevational view thereof.
